FÜR DRAHTLOSE TELEGRAPHIE M. B. H. HALLESCHES, OF BERLIN, GERMANY, A
CORPORATION OF GERMANY.

VACUUM-TUBE OSCILLATOR.

Application filed November 16, 1922, Serial No. 601,261, and in Germany November 21, 1921.

As is well known, the best operating conditions in the use of tube senders are attained when both the anode coupling circuit and the grid coupling circuit have definite values suitable for the circumstances under which the sending is effected. The type of coupling used, i. e. whether inductive or capacitive, is a matter of no consequence whatever. As is well known from published experiments, these correct couplings correspond with the anode alternating current potentials and grid alternating current potentials. It is further known that the anode coupling may be increased within a relatively wide range beyond the most favorable proportion without materially reducing the efficiency of the tubes. However as far as the grid couplings are concerned, the arrangements heretofore provided are very sensitive. For this reason it is usually sufficient if, in operating a sender provided for a wide range of wave lengths, the anode coupling is varied step by step, so that a single adjustment of the anode coupling is made for a number of wave lengths. On the contrary, usually a continuous changing of the grid coupling is necessary, that is, the grid coupling must be changed whenever the wave length is changed. If the grid coupling becomes too loose, then the output of the tube drops to a considerable extent; if it is too tight, then the internal tube losses increase and the tubes are thereby endangered. Arrangements for the continuous varying of the grid coupling are rather expensive.

If so-called intermediate circuit senders are used in which the intermediate circuit is arranged as a well known three-point circuit, then the tube coupling may be left mechanically unchanged in a sender that is suitable e. g. for four wave lengths i. e. 500 to 2000 meters. However, in this case the coupling conditions of the tubes are not the best for all the wave lengths. They will vary more or less. This variation is the greater, the greater the high frequency resistance of the intermediate circuit. The adjustment is effected in such a manner that the best couplings are tuned for the longest wave. When shorter waves are used then the anode coupling increases. This in itself is only slightly harmful, if at all, but at the

same time the grid coupling increases with serious loss of efficiency of the sender tube.

It is desirable to provide means in senders having variable grid coupling for changing the grid couplings without harmful effects on the tubes, and furthermore to provide means by which the increases in grid potential that arise in intermediate circuit senders may be made harmless. In both cases however, a direct changing or branching off of the high frequency circuit is not taken into account.

The present improvement has to do with the provision of such means. It consists in this that a condenser is connected in the grid circuit, in an itself well known manner, and a resistance is connected in parallel with the condenser. In accordance with the present invention, this resistance is made variable whereby the harmful effect of too high grid potential on the tubes is eliminated. After the tuning of the sender to the shorter wave length, this resistance is more or less increased in accordance with the increase in the grid potential.

Fig. 1 is a diagrammatic representation of a circuit arrangement embodying the invention.

Fig. 2 graphically illustrates the manner of operation of such arrangement and,

Fig. 3 is a diagrammatic representation of a modified form of the invention, particularly adapted for use in wireless telephony.

In the circuit arrangements shown in the drawing, the grid circuit includes a condenser 1 with which a variable resistance 2 is connected in parallel. This resistance operates in the following manner:

The grid of the oscillating tube is as is well known, charged, and this charge must flow off through the resistance 2. Due to this a potential will arise at the terminals of the resistance which affects the grid negatively. In Fig. 2, time is represented on the abscissa. The useful values of the grid potential, the anode current and the anode potential are indicated on the ordinate. The curve $V_g \sim$ denotes the grid potential. The curve $ia \sim$ represents the anode current and the curve $V_a \sim$ the anode potential. V_g is the value of the grid voltage corresponding to current value ia at which the current $ia \sim$ reaches the saturation point. If the ampli-

tude of $Vg \sim$ is increased (curve Vg') then obviously the losses in the tubes must increase without any material increase in the output of the tubes. By providing the resistance 2 shown in Fig. 1, a grid potential is produced by which the zero line of $Vg \sim$ is pushed downwards, and the alternating curve $Vg'' \sim$ will be obtained which again reaches only to the potential $Vg \sim$ for which the saturation point of ia is attained. By assuming a correct anode coupling we will now have a certain grid discharge direct current. This may be easily measured by means of a Deprez instrument which should be connected in the branch containing the resistance 2. If the grid potential $Vg \sim$ becomes too large then this grid direct current will also increase. If the grid potential is regulated until it reaches its initial value by increasing the resistance 2, then the original favorable conditions will be obtained.

The above described arrangement for balancing the grid potential that influences the tubes may, for example, be used in the well known telephone circuit arrangement, shown in Fig. 3, in which the speech potential is impressed on the grid of the generator tube. In parallel with the condenser 1, I provide in series a variable resistance 2, a speech transformer 5 and two air core choke coils 3 and 4. The primary winding of the transformer is provided in a circuit comprising the telephone transmitter 6 and the battery 7 therefor. As is well known, this circuit arrangement will operate properly if in its normal condition the saturation value of the grid potential is not reached, this occurring only when additional positive speech potential is impressed on the grid. When negative speech potential is impressed on the grid, the antennæ current will decrease. The grid coupling must therefore be more loosely adjusted in the case of telephony than in telegraphy. Relatively slight variations must be effected, and it would be too complicated if it were desired to make the grid potential variable by varying the coupling of the grid to the oscillating circuit or the like.

It is much simpler to vary the effect of the

grid potential, which is uncoupled from the oscillating circuit, on the tubes by varying the resistance 2 to a suitable extent.

Having described my invention, what I claim is:

1. In a circuit arrangement, a thermionic tube arranged to produce oscillations, a grid condenser in the grid circuit of said tube, a grid leak in parallel with said condenser, means for applying modulating potential to said condenser, and means for preventing the inflow of carrier current into said first means.

2. In a circuit arrangement, a thermionic tube arranged to produce oscillations, a grid condenser in the grid circuit of said tube, a circuit consisting of a high frequency choke coil, a grid leak, a source of modulating potential, all in series, across said condenser.

3. In a circuit arrangement, a thermionic tube arranged to produce oscillations, a grid condenser in the grid circuit of said tube, means for applying modulating potential to said condenser, and means for preventing the inflow of carrier current into said first means.

4. In a circuit arrangement, a thermionic tube arranged to produce oscillations, a grid condenser in the grid circuit of said tube, a circuit including a high frequency choke coil, and a source of modulating potential in series across said condenser.

5. In a circuit arrangement, a thermionic tube having its input and output circuits coupled to produce oscillations by an inductance coil forming a three point coupling, a grid condenser shunted by a variable grid leak in said input circuit, and means for applying a modulating potential to said grid condenser.

6. In a circuit arrangement, a thermionic tube arranged to produce oscillations, a grid condenser in the grid circuit of said tube, a variable grid leak in parallel with said condenser, means for applying modulating potential to said condenser, and means for preventing the inflow of carrier current into said first means.

WALTER SCHAFFER.
